The ornamental design for a bioelectrode, as shown and described.

DESCRIPTION

FIG. 1 is a perspective view of the bioelectrode;

FIG. 2 is a front view thereof;

FIG. 3 is a rear view thereof;

FIG. 4 is a side view thereof;

FIG. 5 is the opposite side view thereof;

FIG. 6 is an end view thereof; and,

FIG. 7 is the opposite end view thereof.
